Specification for Design.

Patented Nov. 15, 1921.

Application filed August 16, 1920. Serial No. 403,948. Term of patent 3½ years.

To all whom it may concern:

Be it known that I, ALBERT E. SEHLBACH, a citizen of the United States, residing at Chicago, in the county of Cook and State of Illinois, have invented a new, original, and ornamental Design for Sundae-Dishes, of which the following is a specification, reference being had to the accompanying drawing, forming a part thereof.

I claim:

The ornamental design for a sundae dish as shown.

ALBERT E. SEHLBACH.
